HATCH FOR TRAWLERS

Frank J. Luketa, 5567 Greenwood, Seattle, Wash.
Filed May 3, 1960, Ser. No. 26,555
5 Claims. (Cl. 114—201)

This invention relates to a trawling vessel, illustrated as one intended for catching shrimp, but in no sense to be understood as limited to such use. In particular the present invention concerns the means whereby decapitated shrimp bodies are delivered selectively to appropriate hold spaces wherein they are refrigerated and held until the vessel reaches a market.

Companion applications have explained how the net is hauled in and reset, and how the catch is segregated from the debris which always comes up with it in the net, and disposed of, and the heads are removed and disposed of. Similar features are incorporated in the drawings of this invention, but the hatch and chutes whereby the segregated, decapitated bodies are stowed in appropriate hold spaces, and the relationship between such hatch and chutes on the one hand and other gear, structure, and equipment on the other hand, constitute the subject matter of this invention.

The present invention has as its object the provision of shrimp-guiding chutes in association with a hatch and hatch cover, whereby despite limited deck spaces and certain interfering structure in the hold space the shrimp bodies may be distributed to and stowed within intended outboard hold spaces or bins, with minimum attention or labor, and without obstructing the normal opening or closing of hatch covers, or access within the hold through the hatch. It also provides free access to the hold spaces for icing, whenever necessary.

The accompanying drawings show the present invention installed aboard a vessel whereon are installed the other gear, structure, and mechanism mentioned, and illustrates the cooperative relationship of all thereof. The showing is to be taken as illustrative and not restrictive.

FIGURE 1 is a general plan view of the after deck of such a vessel.

FIGURE 2 is a side elevational view, partly broken away, of the same.

FIGURE 3 is a transverse sectional view, at the line 3—3 of FIGURE 1.

FIGURE 4 is an isometric view, broken away, of the hatch and associated parts of this invention, in their operative positions.

FIGURE 5 is an isometric view, similar to FIGURE 4, but showing parts in the open position, affording free movement of persons and cargo through the hatch.

FIGURE 6 is an enlarged side elevational view, broken away, with parts in position corresponding to FIGURE 2.

The trawler hull is designated in general by the numeral 9, and has a stern 90, deck 91, and bulwarks 92. A deck house 93 is usually placed somewhat forward of amidship, and a mast 94 and boom 95 rise just aft of the deck house. Stanchions S1, S2 secure the doors when the net is being hauled in. A hatch 8 and main hatch cover 80 afford access to the hold space where refrigerated shrimp are stowed pending their marketing, while a smaller auxiliary hatch cover 81 affords access to chutes 82 leading, as will be explained more fully hereinafter, to the stowage space. A ramp structure generally designated by the numeral 1 extends outboard aft of the stern, during trawling, and guides the net during hauling in and hauling out by the drums of the winch means 6, installed on deck just aft of the mast and boom.

The ramp structure includes transverse rollers 10 and 12 extending between side guides 11 to constitute a platform over which the net is dragged by haul-in lines L1, L2 or haul-out line H, the ramp structure being releasably

2

supported at 14 in its position of use, but being swingable about the axis of its inboard roller 10 to an inboard stowed position. Line guide means 3, 31, 32 are used as explained in the companion application for guidance of the haul-out line and net, while paired upstanding line guides 13a, 14a and 13b, 14b guide the haul-in lines L1, L2, with the respective sweep lines and curtains connected, during hauling in. Jack means 14c (FIGURE 3) allow the inside guides 14a, 14b to be raised and lowered.

10 The winch means 6 includes a number of independently operable, coaxially disposed drums oriented athwartwise. The drums 61a, 61b carry the trawl warps T1, T2 whereby the net is dragged during trawling such warps running through guide blocks 96a, 96b and over opposite sides 15 of the vessel, near stanchions S1, S2 where water reaction doors are secured when the net is hauled in. Drums 62a, 62b wind on the hauling lines L1, L2 which are connected to the net in lieu of the trawl warps in the latter phase of hauling in, and central drum 63 reels in the net itself. Drums 64a and 64b carry lines for various purposes, the 20 combination haul back and try net line H being wound on drum 64b and the utility lifting line U on drum 64a.

In addition the vessel includes segregating means, indicated generally at 7, which includes a flexible bin bottom 25 74 between fixed side walls, and means 75a, 75b, 76a, 76b, 76c and 77 for elevating the bottom 74 to spill the catch onto segregating table 72, all as explained more fully in my companion application on the Segregator, Serial No. 20,581, filed April 7, 1960. Debris is sent 30 overboard by way of chutes 70, assisted by water jets 70a, and decapitated bodies are collected in containers 71. These containers are then hand-carried to the mechanism which is the subject of this invention, for emptying, as is suggested in FIGURE 4 hereof.

35 There is but little deck space, and the winch 6 and segregating means 7 occupy much of this, yet access must be had by way of the hatch to the hold space. Accordingly, the chutes for disposal of the shrimp bodies are installed within the hatch, associated with the hatch cover, 40 but in such a way that access to and from the hold space is not so restricted as to be impossible at any time, either through the main hatch upon raising the hatch cover 80, or through the auxiliary hatch upon raising the smaller hatch cover 81. Also, these chutes must not hinder raising or securing of the respective hatch covers.

45 The main hatch cover 80 is hinged along its forward edge, at 83, to the hatch coaming 8. It can be in its closed and secured position, as shown in FIGURE 6 in full lines, or in its open position, as shown in dot-dash lines. The smaller auxiliary hatch cover 81 is hingedly mounted at 85 to the main hatch cover 80, to cover a 50 small hatch opening in the latter, as in all the figures in full lines, or to be swung aside as shown in dot-dash lines in FIGURE 4. Suitable securing means 88 are provided for each hatch cover.

55 The purpose of the auxiliary hatch and cover 81 is largely to enable the catch to be delivered into the hold spaces intended to receive it, without exposing the entire main hatch, but it is frequently necessary for a member of the crew to enter or leave the hold to ice each additional layer of shrimp without opening the main hatch. The auxiliary hatch is large enough for this, and a ladder 97 is hung from brackets 86 beneath the main hatch for use in such cases. Before the main hatch cover 80 is 60 swung up the ladder can be detached and placed as in FIGURE 5.

65 The auxiliary hatch cover 81 covers the upper end of vertical chutes 82 which are fixed to the main hatch cover 80, within the smaller hatch. While the cover 80 is closed these chutes 82 lead into the upper ends of chutes or extensions 84 which are directed laterally at their lower ends, and are pivotally mounted at 87, at their upper

ends, to the vertical chutes 82. The chutes 84 extend laterally, as stated, in order to direct the catch which is dumped into a chute 82 laterally into an outboard hold space or bin 99 (see FIGURE 4), wherein the catch is stowed and refrigerated. The chutes 82 and 84 at each side are divided, since the chute 84 as a whole must straddle a stanchion 99a which supports the deck and which locates fore-and-aft bin boards 98a and athwartwise bin boards 98b, so by dumping the container 71 full of decapitated shrimp bodies into one or another chute 82 each bin in turn is filled and iced, and then another, and so on. The chute extensions 84 are lashed in their outswung positions to the stanchions 99a during stowing of the catch.

When the main hatch cover 80 is to be raised, the chute extensions 84 are released from the stanchions 99a, and can be swung inboard and secured together by lashing 84a (FIGURE 5), which withdraws their lateral extensions inside the outline of the hatch 8, and avoids interference when the hatch cover 80 is swung up, carrying the attached chutes 82 and 84. After the cover 80 is raised and while it rests against the winch 6, as in FIGURE 5, the lashing 84a is released and chutes 84 fold flat against the cover 80, to allow unimpeded access to the hold at dockside, when unloading the shrimp cargo. The hatch 8 is just far enough astern of the winch 6 that the drum flanges afford a convenient rest for the upraised cover 80; see FIGURE 6.

The shrimp bodies are collected in a receptacle 71 near the segregating table 72, and when filled this receptacle is dumped down one or the other divided chute 82, and is directed by the chute 84 laterally into a hold space 99. If access to the hold is necessary, as usually it would be for icing the catch, a crew man can enter through the auxiliary hatch and down the ladder 97. When unloading the catch, or when for any other reason freer access is required into the hold, the main hatch cover 80 is swung up, rests against the winch 6, and the chutes 84 are moved into the full line positions shown in FIGURE 5. The hinged mounting at 87 of the chutes 84 permits the latter to swing inboard, and enables the cover 80 to swing without interference, yet the lateral extensions of chutes 84 direct the catch outboard of the hatch outline, when the hatch cover 80 is secured and the chutes 84 are swung outboard and secured.

I claim as my invention:

1. A vessel having a main hatch affording access between a deck above and hold space beneath the deck, a raisable main hatch cover for opening or closing the hatch, said hatch cover being formed with an auxiliary

It is 18 years since I started my work with the first group of blind children in India, and during these 18 years I have seen many changes and growths in the field of education for the blind. The first group of blind children I taught were 4 years old and now they are 22 years old. They have all graduated with honours from the secondary school, and are now in the first year of college. They are all married and have families of their own. The first group of blind children I taught were 4 years old and now they are 22 years old. They have all graduated with honours from the secondary school, and are now in the first year of college. They are all married and have families of their own.

For both natural and synthetic, 17-hydroxy-estradiol, the α -ketone and its corresponding ester and ether, and the 17-hydroxy-17,20-dihydro- β -estradiol, the α -ketone and its corresponding ester and ether, were synthesized. The α -ketone and its corresponding ester and ether, and the 17-hydroxy-17,20-dihydro- β -estradiol, the α -ketone and its corresponding ester and ether, were synthesized.

hatch also admitting to the hold space, a two-part chute means extending through the auxiliary hatch, one such part being fixedly supported upon the main hatch, within the outline thereof, and the other such part being hinged

5 edly mounted beneath the first part, and having a laterally directed lower terminus extending outboard of the outline of the main hatch when in position of use, but swingable inboard thereof by its hinged mounting, for movement through the main hatch upon raising of the main hatch cover, and an auxiliary hatch cover for closing the auxiliary hatch and the upper end of said chute means.

15 2. A vessel as in claim 1, wherein the main hatch cover is hingedly mounted along one edge, and the hinge mounting of the lower part of the chute means has its axis angularly disposed with relation to the hinge axis of the main hatch cover.

3. A vessel having a main hatch opening, a

3. A vessel having a main hatch affording access between a deck above and hold space beneath the deck, a main hatch cover swingably mounted at one edge for swinging open or to closed position, a ladder, and means carried by said main hatch cover radially outwardly of its axis of swing for removably supporting the upper end of said ladder, for access to and removal thereof upon or before raising the main hatch cover.

25 4. A vessel as in claim 3, the main hatch cover having an auxiliary hatch, an auxiliary hatch cover for closing or affording access through the auxiliary hatch, the ladder and its supporting means being located for access through the auxiliary hatch.

30 5. A vessel having a main hatch affording access between a deck above and hold space beneath the deck, a main hatch cover hingedly mounted along one edge for closing or opening the hatch, said hatch cover being formed with an auxiliary hatch also admitting to the hold space, chute means hingedly mounted upon the main hatch cover to swing upon an axis perpendicular to the hinge axis of the main hatch cover, an auxiliary hatch cover for closing or opening the auxiliary hatch and the upper end of said chute means, and a projection at the lower end of said chute means positioned laterally beyond the outline of the main hatch when the chute means depends in operative position, but movable within such outline when the chute means is hinged inwardly, thus to allow opening of the main hatch cover.
